LIGHT PLYWOOD SHIPPING CONTAINER

Nathan Tufts, Greenfield, Mass., assignor to The
New England Box Company, Greenfield, Mass.,
a corporation of Massachusetts

Application September 16, 1935, Serial No. 40,709

5 Claims. (Cl. 217—12)

This invention relates to a light weight wooden box construction of the knock down type and particularly of the large size frequently known as a packing or shipping case.

5 An object of the invention is to provide a simple arrangement of members, which may be shipped in a one piece mat form and which may be easily and quickly assembled in box form, as desired for use, without the necessity of employing tools therefor or any additional parts.

10 A feature of the invention is to make a container of packing-box size, which is sufficiently solid and of a balanced construction so that it will stand rough treatment to which it may be subjected, while reducing the weight thereof to a minimum. A further feature of my improved construction is that the container is very tight when sealed serving to protect the contents against rain, dust, and the like.

20 With the usual construction of wire-bound packing boxes, it is necessary in shipping a load of boxes in mat form, to assemble two or three boxes and fill them with the necessary quantity of box ends. When the shipper desires to use 25 these boxes he must then pick over and select the end members which fit the various mats, arrange the structure in box form, and unite the ends of the wire bales thereon after the goods have been packed and the lid closed.

30 In my improved box construction all the members are arranged in their correct positions in the mat form and it is simply a question of folding and unfolding the members to the desired position, filling the boxes, closing the lid and applying an adhesive tape to prepare the box for 35 shipment. Such simple operations may be readily performed by female labor.

Further features and advantages will be more 40 apparent from a detailed description of the embodiments of my invention illustrated in the drawings, in which:

45 Figure 1 is a perspective view of a box in assembled position with the lid thereof raised prior to packing and sealing.

Figure 2 is a perspective view of a box of relatively great length as compared with width and depth and showing a band applied around the middle thereof to strengthen the same.

50 Figure 3 is a perspective view similar to Fig. 1 without the lid and with portions broken away to show the construction thereof.

Figure 4 is a perspective view of a modification 55 of my invention showing additional binding tapes applied around the ends of the box.

Figure 5 is a plan view of a box such as shown in Fig. 1 when arranged in mat form.

Figure 6 is a vertical transverse section taken on the line 6—6 of Fig. 2.

Figure 7 is a vertical section through the mat 5 taken on the line 7—7 of Fig. 5.

Figure 8 is a plan view of a section of one type of tape which may be employed in connection with my invention, one portion being broken away to show more clearly the construction thereof. 10

In the drawings, as assembled box is indicated at 10 and is composed of a bottom member 11, side sections 12 and 13, ends 14, 15 and top or lid 16. These top, bottom, and side sections are preferably joined along their longitudinal edges by 15 suitable strips of tape 17, which are preferably sufficiently flexible to act as a hinge for the cover member and also of sufficient strength to hold the various sections of the box together even though it is given rough treatment during handling and 20 shipment.

The various sections of the box are preferably made of ply-wood which may be fairly thin. For example, I have found that a $\frac{3}{16}$ " ply-wood is sufficiently strong for most practical purposes in 25 this construction. Even a $\frac{3}{30}$ " ply-wood is sufficient in a small box, say 12"x12"x18". Wood veneer or other light wood sheets may be substituted for the ply-wood, if desired, although the 30 ply-wood is to be preferred due to its great 30 strength in proportion to weight. The bottom, side and top sections are provided at their end edges with cleats 18 which may be stapled or otherwise secured thereto to promote rigidity and 35 form a rather substantial frame-work at each end of the box. The end sections preferably comprise simply a flat sheet of thin wood.

Each cleat is preferably formed at one end with a mortise joint 19 and at the other end with a tongue or tenon 20. When the box is assembled the four cleats at each end interfit to provide a rigid joint at each corner, thereby preventing any movement of the bottom, top and side sections longitudinally relative to each other. By using cleats of the type illustrated, in a box 40 that is square in transverse cross-section it is possible to make them all of the same size and shape, thus greatly simplifying the manufacture thereof. Other types of joints, such as a mitred joint, or combinations of mitring with mortise and tenon, may be employed in joining the ends of the cleats, although I prefer the form shown because of its strength and simplicity of manufacture. 45

In assembling the box it is ordinarily satis- 55

factory to apply tapes only along the longitudinal edges thereof, with an overlap of the tape on each side sufficient to provide a tight and firm joint. Tapes may also be applied at one or both of the vertical edges of the end sections of the box on the inside thereof as at 21 and 17b to insure greater tightness, although this is not necessary. These tapes also assist in maintaining the ends in proper position although this may be accomplished in other ways as by the use of small nails or tacks fastening the ends of the cleats or simply by the contents of the box.

In the case of a box which is relatively long with respect to the other dimensions it may be desirable to apply a band 22 around the middle thereof, as shown in Fig. 2. Such a band may be made of metal or other suitable material and fitted with interlocking prongs and openings 23 to hold the same in place. Tapes in addition to the longitudinal tapes may be applied to the box around the ends thereof, as shown in Fig. 4 and 25, thus producing a bound effect for the structure and lending added strength to the corners to prevent splitting of the longitudinal tapes along the meeting edges of the sections. If desired, the tapes 25 may be used alone without the longitudinal tapes. This provides a rather strong construction but is not completely sealed.

The tapes employed in my improved box construction may be of any suitable type such as gummed paper or cloth. I have found that a tape gummed on one side and made of relatively heavy, tough paper, formed in part of old rope or hemp and impregnated with latex, is very satisfactory. The composite tape illustrated in Figs. 1 and 8 is particularly suitable for the purpose, this being made up of two layers of paper or cloth 26, 27, held together by adhesive 28 and reinforced by a string 29, or other suitable 40 tough filament. This string may be arranged in a sinuous form to provide alternate loops 30, 31 extending transversely of the tape to give it additional transverse strength. When employing paper tapes, according to the preferred form 45 of my invention, they should be applied with the grain of the paper running transversely of the box to afford the maximum strength.

In making up my improved box in mat form, as shown in Fig. 5, the end edges of the top, bottom and side sections are stapled or otherwise fastened to their respective cleats. The tapes 17 are then applied to the three adjoining edges of the four sections, in such a way as to provide a sufficient clearance 32 to allow for bending of these various sections at right angles 55 to each other during folding of the mat into a completed assembly. The cleats on top 16 and bottom 11 preferably do not extend to the very edges of their respective sections but leave a space at each end thereof equal to the thickness 60 of the ply-wood so that these two sections will overlap the edges of the side sections in folded and assembled position. Thus the top and bottom sections are supported by the side sections 65 and much of the strain on the tapes is relieved. The width of the various sections and their spacing should be so selected as to insure this relationship, i. e. the sections should be spaced just the thickness of the ply-wood. If desired the 70 construction might be modified slightly to cause each section to overlie the edge of one adjacent section and to have its own edge overlapped by the other adjacent section.

A strip of tape 17a, similar to the tapes 17, 75 may be applied to the free edge of either the

side or top section to act as a closing and sealing means when the box is finally closed. All that is necessary in closing the box in its simplest form, is to moisten the free edge of the tape 17a and attach it to the free edge of the top or side. The end pieces may be attached to the sides 12 and 13 by tapes 17b and when folded down flat against the side sections will provide a mat no thicker than the thickness of the cleats 18. If desired, the free ends of these end sections may be held in place against the side sections by gummed strips of tape 33 or other suitable means. This will prevent damaging the end pieces in the handling of the mat.

In assembling the box it is simply necessary 15 to tear the strips 33 loose, raise the two end sections and fold the mat along the lines 34, 35. I prefer to then nail the end sections to one or more of the cleats adjoining them, for example, the two cleats 18a and 18b and possibly 20 also cleat 18 (Fig. 1). In lieu of this, however, or in addition thereto, two more tapes 21, 21 may be employed along the free vertical edges 25 of the end sections to attach them to the opposite sides and hold the parts in folded relation during packing. Neither of these expedients is essential, however, since the goods will hold the ends tightly against the cleats. On the other hand, the nails do lend additional strength to the box while the extra tapes 21 assist in more 30 completely sealing the box. After the box is packed the lid is closed and the free edge of the gummed strip 17a is moistened and attached to the free edge of the lid.

The tape employed in my improved construction lends itself to advertising. Furthermore, with my improved construction the shipper need not employ any tools in assembling and packing the box other than possibly a hammer if the end pieces are nailed to the cleats. Such a packing box is also advantageous because of the fact that it may be very readily reused after the tape is broken at one edge by applying another strip of tape thereover or in place thereof. Such additional tape may be supplied in roll or other suitable form to the users of the boxes. The end pieces may be directly provided with the extra strips of tape 21 at their free edges, which may be simply moistened and stuck in place by the shipper to hold the box in folded condition. If the box is to be returned in flat mat form to the original point of shipment the strips 21 are simply severed and may then be readily replaced when the box is again assembled and used. As previously explained, the top and bottom sections are illustrated as overlapping and resting on the side and end sections. This construction keeps the box from flexing too much and from cracking if subjected to heavy weight as frequently occurs when packing boxes are piled one 50 on top of another. This overlapping is especially 55 desirable where paper tapes are to be used, since it relieves such tapes from a major portion of the strain which would be otherwise produced.

A distinct advantage of the present construction is that it provides a box of balanced strength. It has been found in testing the box that it sometimes gives way at one point and sometimes at another, thus indicating that there is no waste of material in building up excessive strength at any 70 particular points. Should it be found necessary to provide greater strength along any of the longitudinal edges this may be accomplished by applying an extra strip of tape along one or all of these edges. This added reinforcement is par- 75

ticularly desirable along the edges of the top member since the cleats of this member cannot be nailed readily to the end sections.

In drop tests my improved container has been found to be far superior to cardboard boxes and to stand up as long as wooden boxes of a much heavier construction. Boxes constructed in accordance with my invention may be advantageously used for freight since there are no restrictions applied thereto such as are applied to cardboard containers. Actually however my container protects the contents thereof much better than required by the standards set by railroads and transportation companies.

If desired the tape 11a and the tape 21 may be omitted from the free edges of their respective sections as the boxes are shipped in mat form and these tapes may then simply be supplied from a roll as required at the points where the boxes are assembled and packed.

Corner reinforcement is sometimes desirable and may be supplied in any convenient manner, as by applying a cloth or paper cap adhesively to each corner.

The terms and expressions employed herein are used for purposes of description and not of limitation. It is recognized that many modifications of the construction disclosed may be made within the scope of the present invention as defined by the claims which follow.

What I claim is:

1. In a box of the class described, top, bottom, side and end sections formed of plywood, cleats fixed to the end edges of said top, bottom and side sections with the ends thereof fitted to each other to prevent relative lateral movement, adhesive tapes sealing three of the longitudinal corners of said box, adhesive tape applied to the free edge of one of said sections, and adhesive tapes applied to the inside of said box sealing at least one edge of each of said end sections, said tapes comprising the means for retaining said sections in assembled position.

2. In a box of the class described, top, bottom, side and end sections formed of plywood, cleats fixed to the end edges of said top, bottom, and

side sections with the ends thereof fitted to each other to prevent relative lateral movement, adhesive strips applied inside said box to side edges of said end sections to seal said edges, and relatively long and narrow strips of readily flexible paper applied to at least three of the longitudinal corners of said box, said strips comprising the primary means for sealing said corners and holding said sections in assembled position. 5

3. In a box of the class described, top, bottom, 10 side and end sections formed of plywood, cleats fixed to the end edges of said top, bottom, and side sections, said cleats being of substantially the same length and having a mortise at one end and a tenon at the other, means for securing said sections together consisting of strips of adhesive 15 tape applied to the longitudinal corners of said box, and strips of adhesive tape joining the end sections and side sections, said top and bottom sections overlying the edges of said side sections. 20

4. A knock-down shipping box arranged in mat form comprising plywood top, bottom and side sections disposed side by side in a continuous line, cleats having ends formed to cooperate and interengage with each other fixed to the end edges of 25 said top, bottom, and side sections, strips of adhesive tape applied to the three sets of adjacent edges of said sections to form hinges and seals therefor, and end sections hinged to said sides adjacent the ends thereof by adhesive strips. 30

5. A knock-down shipping box arranged in mat form comprising plywood top, bottom and side sections disposed side by side in a continuous line, cleats having ends formed to cooperate and interengage with each other fixed to the end edges of 35 said top, bottom, and side sections, strips of adhesive tape applied to the three sets of adjacent edges of said sections to form hinges and seals therefor, an end section hinged to one side section adjacent a cleat thereof by an adhesive strip, a 40 second end section hinged to the other side section by an adhesive strip adjacent the cleat thereof on the opposite side of said mat, and temporary means for holding the free ends of said end sections flat against said side sections. 45

NATHAN TUFTS.
